UNITED STATES PATENT OFFICE.

EDWARD S. STIMPSON, OF HOPEDALE, MASSACHUSETTS, ASSIGNOR TO DRAPER CORPORATION OF HOPEDALE, MASSACHUSETTS, A CORPORATION OF MAINE.

FILLING CLAMPING AND PARTING MECHANISM FOR LOOMS.

Application filed May 14, 1921. Serial No. 469,503.

To all whom it may concern:

Be it known that I, EDWARD S. STIMPSON, a citizen of the United States, and resident of Hopedale, county of Worcester, State of Massachusetts, have invented an Improvement in Filling Clamping and Parting Mechanism for Looms, of which the following description in connection with the accompanying drawing, is a specification, like characters on the drawing representing like parts.

This invention relates to automatic filling replenishing looms wherein the running filling is replenished prior to complete exhaustion and wherein the old or spent filling is parted between the cloth and the shuttle by parting means mounted upon a shuttle carrier, such as the usual swinging shuttle feeler, so as to be moved bodily, rearwardly and forwardly or toward and from the lay. The object of the invention is to provide an improved, simple, and effective means for operating the filling clamping and parting device when, and only when, a fresh filling carrier is transferred from the magazine or supply to the lay.

The object of the invention is further to provide a construction which may be easily and readily adapted to existing looms.

The object of the invention is further to provide a construction which will yield upon the occurrence of an abnormal resistance to the operation of the filling clamping and parting device.

The object of the invention is further to provide a construction in which the usual switch cam for opening the filling clamping and parting device is eliminated and novel means provided for securing the opening movement.

These and other objects and features of the invention will appear more fully from the accompanying description and drawings and will be particularly pointed out in the claims.

In the drawings:

Fig. 1 is a transverse section of a portion of an automatic filling replenishing loom with a preferred form of the present invention embodied therein.

Fig. 2 is a detail showing a portion of the same parts illustrated in Fig. 1 but in a different position.

Fig. 3 is a view in transverse cross section taken on the line 3-3 of Fig. 2.

55

Fig. 4 is a view in side elevation of a portion of the construction illustrating a different form of supporting bracket.

This construction illustrated is that of the well known Northrop type of automatic filling replenishing loom; and as this construction is familiar to those skilled in the art no detailed illustration or description beyond the features particularly concerned with this invention is necessary.

65

The broad feature of insuring the operation of the filling clamping and parting means when, and only when, a fresh filling carrier is transferred from the magazine to the lay is also disclosed in the patent to Davis 1,084,878, granted Jan. 20, 1914, and this patent also serves to illustrate the general type of mechanism in connection with which a preferred form of the present invention is herein illustrated.

75

The lay 1; the transerrer 2 which upon the call for filling the replenishment acts to transfer the filling carriers, or in this case the bobbins 3, from the magazine or hopper 4 to the lay, or in this case to the shuttle 5, at the replenishing side of the loom; the controlling rock shaft 6 which is rocked upon the indication of substantial exhaustion in the running shuttle and acts to initiate filling replenishment; the breast beam 7; the shuttle feeler arm 8 which rocks and slides on the stud 9, being swung over the lay in front of the boxed shuttle upon the operation of the controlling rock shaft 6 and returned under the action of the spring 10 are parts the construction and operation of which will readily be understood by one familiar with the art such as is disclosed in the patent to Davis above mentioned and the patents therein referred to.

95

The replenishing magazine 4 is provided with the usual guide stop 11 against which the filling carrier or bobbin 3 is brought into position for transfer. The filling carrier to be transferred is yieldingly supported and guided on the side opposite to the stop 11 by the usual movable filling carrier support 12 in the form of a flat finger located adjacent the inner face of the magazine. This supporting finger 12 is connected to 105 a stud 13 extending through the side of

- the magazine and carrying on the opposite side an arm 14. A spring 15 is held between a lug 16 on the magazine and the head 17 of a slide rod 18 connected with 5 the arm 14, the rod being guided in the lug. The stop 11 thus forms one side of a throat which the filling carrier passes from the magazine to the lay, the filling carrier support or finger 12 forming the other side.
- 10 When the transfer 2 is operated to transfer a fresh filling carrier from the magazine to the lay, this filling carrier support yields and supports and guides the filling carrier as it passes to the lay.
- 15 The filling clamping and parting device may be of any suitable form and construction and is shown as generally similar to that illustrated in the patents above referred to. This device is also shown as supported and carried by the usual shuttle feeler 8. The movable blade 19 co-operates with fixed blades, one of which is shown at 20, and the movable blade 19 secures its opening and closing movement about the pivot 21.
- 20 When a replenishment of filling is called for the shaft 6 is rocked in the usual manner raising the arm 22 extending rearwardly therefrom and therethrough rocking the shuttle feeler 8 toward the lay. If the shuttle is properly boxed this feeler will pass in front of the shuttle in the usual manner and the dog 23 will be brought into the path of a bunter on the lay and thereupon the transfrerer 2 will be operated to transfer 25 the filling carrier 3 from the magazine to the lay therebeneath.
- When the shuttle feeler thus swings rearwardly over the lay the filling extending from the filling carrier to be abandoned enters 30 between the members of the filling clamping and parting device which are then in open position. In the case of the type of mechanism to which this invention relates the filling clamping and parting device is closed to clamp and part the filling when, and only when, a filling carrier is actually transferred by the transfrerer from the magazine to the lay. Consequently, if the shuttle be improperly boxed so that it is struck by the shuttle feeler or if the conditions 35 are such that the shuttle feeler, no matter to what extent it may move, does not effect a filling transfer or if for any reason the filling transfer does not actually take place then there can be no severance of the filling by the filling clamping and parting device.

This result is secured in the present invention by operating the filling clamping and parting device through the movement of the filling carrier support 12 which only moves when actual transfer takes place.

The present invention provides a yieldable operative connection between this filling carrier support 12 and the filling clamping and

parting device when in operative position so that in case of any abnormal resistance to a relative movement between these parts there will be no danger of a smash or of damage to the loom.

A supporting bracket 24 is provided for this connection. In Fig. 1 the supporting bracket 24 is shown as supported on the axial stud 25 of the magazine. The bracket is provided with an elongated slot 26 fitting 75 over the stud 25 so that the bracket may be adjusted into any desired position and then locked in place by the nut 27. In Fig. 4 the supporting bracket 28 is shown of a different shape and secured in the required position by being bolted directly to the side of the magazine 4 by a bolt 29. It is obvious that the supporting bracket may thus be secured and held in place in any desired manner. The form shiwn in Fig. 1 enables 85 the bracket to be applied to existing looms simply by placing it over the stud 25 already on the loom and then locking it in place.

This supporting bracket carries a horizontal stud 30 which serves as the fulcrum 90 for an actuator lever by means of which the movement of the filling carrier support 12 is transferred to the filling clamping and parting device. The yieldable feature in this form of invention is effected by making 95 the actuator lever flexible. For this purpose it is made of stout spring wire so proportioned that under normal conditions it has sufficient rigidity to effect the clamping operation but under abnormal resistance to 100 a relative movement between the filling carrier support and the filling clamping and parting device it will flex or yield.

This actuator lever is shown as wound in spiral form at 31 to form a fulcrumed 105 hub fitting over the stud 30. One arm 32 of the lever is bent into U-shape and fits over a stud 33 projecting laterally from the arm 14 connected with the filling carrier support 12. The other arm 34 of the actuator lever is bent horizontally and then laterally and then downwardly to form the portion 35 and then forwardly to form the portion 36 about as shown in the drawings.

The movable member 19 of the filling 115 clamping and parting device is provided with a laterally extending pin 37 at its forward upper end and the parts are so arranged that when the shuttle feeler has carried the filling clamping and parting device into operative position over the filling of the filling carrier to be abandoned this pin 37 will have ridden over the portion 36 of the actuator lever and come into the angle formed between the portions 35 and 36 of 125 the lever, all as shown in Fig. 2.

If now transfer takes place and the filling carrier support 12 is rocked by the actual transfer of the filling carrier from the magazine to the lay in the replenishing operation, 130

then the actuator lever will be rocked about the stud 30 thus raising the stud 37 on the movable member of the filling clamping and parting device and effecting the clamping and parting of the filling. If for any reason whatever there is an abnormal resistance to relative movement between the filling carrier support 12 and the movable member of the filling clamping and parting device, then the actuator lever will flex or yield and thus no injury or damage will occur to any of the parts.

After the clamping and parting operation has taken place the shuttle feeler swings forwardly carrying the end of the filling extending to the fell and moves into a position such as illustrated in Fig. 1. Consequently, the filling clamping and parting device must be brought to open position before it can again function. This result has generally been secured by the use of a switch cam. In the present invention this result is secured by the actuator lever and thus the switch cam is eliminated. When the shuttle feeler swings rearwardly the stud 37 comes against the downwardly extended portion 35 of the actuator lever, and hence the movable blade 19 is rocked into open position.

It is desirable to reinforce and guide the actuator lever to prevent it flexing or yielding when struck by the stud 37 to effect the opening of the filling clamping and parting device. For this purpose an adjustable slotted plate 38 is provided. This plate is mounted on a flange 39 extending laterally from the bracket 24 or 28. The plate 38 is slotted at 40 transversely to the slot in the flange 39. Hence a single bolt 41 serves to adjust and lock the plate 38 into any desired position. This plate 38 is provided with a slot as shown surrounding and extending rearwardly of the downward portion 35 of the actuator lever. It consequently prevents twisting of the lever and reinforces the lever against backward movement when struck by the stud 37.

There is thus provided a very simple and practical mechanism readily applied to existing looms, readily adjusted to existing conditions and of strong and efficient construction. There can be no operation of the filling clamping and parting device unless actual transfer of a fresh filling carrier takes place and when this transfer does take place the operation is effected accurately and surely but without any danger of injury or breakage of the working parts of the loom, due to the occurrence of some abnormal condition.

The adjustment of the supporting bracket and the yieldable feature of the actuator is also of great advantage in assembling and operating the cutter. By this construction the parts are readily positioned so that when the movable cutter blade is actuated to close

the filling clamping and parting device no injurious strain is placed upon the parts after the closing position has been reached.

Having thus described my invention, what I claim as new and desire to secure by Letters Patent, is:

1. An automatic filling replenishing loom comprising a lay, a replenishing magazine for the fresh filling carriers, means for transferring a fresh filling carrier from the magazine to the lay, a filling clamping and parting device movable into position to receive the running filling when the lay is in position for transfer, and an actuator yieldable upon the occurrence of an abnormal resistance and actuated by or through the transfer of the fresh filling carrier from the magazine to the lay to actuate the filling clamping and parting device to clamp and part the filling extending from the filling carrier to be abandoned, the said actuator being positioned to be struck by the filling clamping and parting device upon its movement into position and thereby to effect the opening of the said device.

2. An automatic filling replenishing loom comprising the construction defined in claim 1, together with means for reinforcing the actuator to prevent its yielding when struck by the said device to effect the opening thereof.

3. An automatic filling replenishing loom comprising a lay, a replenishing magazine for the fresh filling carriers, means for transferring a fresh filling carrier from the magazine to the lay, a filling clamping and parting device movable into position to receive the running filling when the lay is in position for transfer, a movable filling carrier support moved by the filling carrier upon its discharge from the magazine to the lay, a bracket and means for mounting it rigidly on the loom frame, and an actuator lever fulcrumed on the said bracket engaging at one end the filling carrier support, engaging at the other end the filling clamping and parting device and yieldable upon the occurrence of an abnormal resistance to relative movement of the said support and of the said device but acting under normal conditions to actuate the said device upon the movement of the filling carrier support to effect the clamping and parting of the filling extending from the filling carrier to be abandoned.

4. An automatic filling replenishing loom comprising the construction defined in claim 3 in which the actuator lever is in itself resilient and yields by flexion.

5. An automatic filling replenishing loom comprising the construction defined in claim 3 in which the bracket is adjustably mounted upon the usual axial stud of the replenishing magazine.

6. An automatic filling replenishing loom

comprising a lay, a replenishing magazine for the fresh filling carriers, means for transferring a fresh filling carrier from the magazine to the lay, a filling clamping and parting device movable into position to receive the running filling when the lay is in position for transfer, a filling carrier support pivotally mounted in the magazine and movable by the filling carrier upon its discharge 10 from the magazine to the lay, a supporting bracket rigidly secured to the loom frame and extending adjacent the filling carrier support, a flexible actuator lever fulcrumed on the bracket and engaging with one arm 15 the pivoted filling carrier support and having its other arm provided with a downwardly extended portion followed by a forwardly extended portion, a stud on the filling clamping and parting device acting to 20 open the said device when upon movement thereof it comes into contact with the downwardly extended portion of the actuator lever and acting to effect the closing of the 25 said device when the actuator lever is rocked to raise the forwardly extended portion thereof.

7. An automatic filling replenishing loom comprising the construction defined in claim 6 in which a reinforcing plate is adjustably 30 mounted on the bracket to guide the actuator lever and limit the yielding movement thereof when struck by the stud to effect the opening of the filling clamping and parting device.

8. In an automatic replenishing loom a 35 bracket, a stud extending therefrom, a flange extending therefrom parallel with the stud, a spring wire lever having a fulcrum on the said stud, and a slotted guiding stop plate, adjustably mounted on the flange and engaging one arm of said lever. 40

9. An automatic filling replenishing loom comprising a lay, a replenishing magazine for the fresh filling carriers, means for transferring a fresh filling carrier from the 45 magazine to the lay, a filling clamping and parting device movable into a position to receive the running filling when the lay is in position for transfer, a movable filling carrier support moved by the filling carrier 50 upon its discharge from the magazine to the lay, a bracket secured to the side of said magazine in proximity to said filling carrier support, an actuator lever fulcrumed on said bracket engaging at one end the filling carrier support, engaging at the other end the filling clamping and parting device and yieldable upon the occurrence of an abnormal resistance to a relative movement of said support and said device, but acting under 55 60 normal conditions to actuate said device upon the movement of the filling carrier support to effect the clamping and parting of the filling extending from the filling carrier to be abandoned. 65

In testimony whereof, I have signed my name to this specification.

EDWARD S. STIMPSON.
